UNITED STATES PATENT OFFICE.

JUSTIN L. FEARING, OF JAMAICA, NEW YORK, ASSIGNOR TO WESTERN ELECTRIC COMPANY, INCORPORATED, OF NEW YORK, N. Y., A CORPORATION OF NEW YORK.

PHONIC DIAPHRAGM.

Application filed August 29, 1923. Serial No. 659,876.

This invention relates to phonic diaphragms, particularly to the direct acting type, and has for an object to simplify the association of the diaphragm with respect to its driving means.

This is accomplished by providing a direct acting diaphragm with means which wholly or partly support the device which drives or actuates it.

For further details of the invention, reference may be made to the drawings in which Fig. 1 is a side elevation partly in section of one form of the invention. Fig. 2 is a plan view of the conical diaphragm shown in Fig. 1. Fig. 3 is a detailed view of the means for supporting the actuating device. Fig. 4 is a side elevation partly in section with a modification.

Referring in detail to the drawings, the phonic diaphragm 1 is illustrated as a cone of paper, mica or bristol board or the like. The periphery of this cone may be reenforced if desired, by means of the integral corrugation 2. This cone is adapted to rest directly on the fabric 3 which may be a floor carpet, a table cover or the like. Adjacent the apex of the cone is fastened the support 17 which may be of sheet metal and tripod in form. The three legs of this support are bent near their extremities to an angle to conform to that of the cone and are apertured and fastened to the cone by suitable means such as the screw bolt 4. Each of the legs of the support 17 is bent to form a three-point support for the telephone diaphragm 5 of magnetic material. Resting on the diaphragm 5 is a telephone receiver casing 6 which is of a smaller diameter than that of the diaphragm 5. The casing 6 contains electromagnets, the circuit of which may be connected to any suitable source of electric telephone currents. In order to obtain a tension in the phonic diaphragm 1, a weight 7, the value of which can be determined by trial, is placed on the receiver casing 6.

In the modification shown in Fig. 4, cone

1 and fabric 3 are supported on a platform 8 to which is suitably fastened by means such as screws 9, the yoke 10 which carries means to provide a suitable tension in the phonic diaphragm 1 as well as means to suitably tension the telephone diaphragm 5. To this end the diaphragm 5 has its periphery engaged between yieldable material 11 carried in a plurality of pockets in the casing 12. By turning the screw 13 which is screw threaded in the top of the casing 12 and which bears on the top of the telephone casing 6, the distance between the diaphragm 5 and the pole pieces 14 may be adjusted. The screw 16 is screw threaded in the yoke 10 which carries a spring 15, one end of which bears on the top of the casing 12. By turning the screw 16, the tension in the phonic diaphragm 1 may be regulated.

The invention provides a large direct acting diaphragm of the inertia type, that is the diaphragm wholly or partly supports the telephone instrument.

The conical diaphragm may be of the order of 14 to 18 inches in diameter and 3½ to 4 inches high.

What is claimed is:

1. A large direct-acting conical diaphragm adapted for horizontal mounting, and means disposed at the apex of said diaphragm for supporting a telephone receiver, said means having a plurality of points in a plane parallel to the base of said diaphragm for contacting with the vibratory member of the receiver.

2. A large direct-acting conical diaphragm, and means carried by said diaphragm at its centre, said means having three points in a horizontal plane whereon a telephone receiver may be detachably supported on its vibratory member.

In witness whereof, I hereunto subscribe my name this 18th day of August, A. D. 1923.

JUSTIN L. FEARING.
